GAS RANGE

John G. Hoff, Mansfield, Ohio, assignor to The
Tappan Stove Company, Mansfield, Ohio, a
corporation of Ohio

Application September 17, 1936, Serial No. 101,277

6 Claims. (Cl. 126—39)

This invention relates to a gas range having a flat cooking top having therebelow one or more cooking compartments, the top of the range preferably having a plurality of top burners arranged in groups, each group having a lid or cover thereon adapted to be opened to render the burners accessible.

In ranges of this character it is desirable to have a flue leading from the cooking compartment or compartments to take off the fumes and products of combustion. Such a flue usually extends a substantial distance across the back of the range. The lids or covers normally are disposed over the cooking top burners and it is desired to provide means for receiving and guiding such lids when they are opened so that they may be disposed out of the way. In view of the fact that it is necessary to have a flue outlet from the cooking compartments, the provision of means for receiving the cooking top covers presents a problem and it is toward this feature that this invention is particularly directed.

One of the objects of the invention is to provide a gas range having a flat cooking top and one or more cooking compartments disposed therebelow and a plurality of top burners arranged in groups on the cooking top, together with lids or covers which normally cover the top burners and means for receiving and guiding such lids when they are opened.

Another object of the invention is to provide a range having a flat cooking top which has a plurality of spaced openings therein in each of which is arranged one or more top burners, such cooking top having lids which cover the top burners and having also a rearwardly extending portion having slots therein which serve to receive and guide the lids respectively when they are moved to a position to render the top burners accessible.

Another object of the invention is to provide a range of the character described which possesses the features and advantages hereinbefore referred to and which is well adapted for production at a minimum cost.

Further and more limited objects of the invention will appear as the description proceeds and by reference to the accompanying drawings in which Fig. 1 is a top plan view of a range having the features and advantages hereinbefore referred to; Fig. 2 is a horizontal sectional view on the line 2—2 of Fig. 5 looking upwardly in the direction of the arrows in Fig. 5; Fig. 3 is a fragmentary view in rear elevation showing the back of the range shown in Fig. 1; Fig. 4 is an enlarged

fragmentary vertical sectional view on the line 4—4 of Fig. 1 and looking in the direction of the arrows; Fig. 5 is a view similar to Fig. 4 showing the cover in the closed position; Fig. 6 is a fragmentary vertical sectional view on the line 6—6 of Fig. 1 with the cover in closed position; Fig. 7 is a top plan view of a modified form of my invention disclosing a range having two ovens and two groups of top burners; Fig. 8 is a fragmentary horizontal sectional view similar to Fig. 2; Fig. 9 is a fragmentary sectional view on a reduced scale taken substantially on the line 9—9 of Fig. 7; Fig. 10 is a top plan view of another modified form of range showing a slightly different arrangement of top burners; Fig. 11 is a fragmentary vertical sectional view similar to Fig. 8 and looking upwardly; Fig. 12 is a fragmentary vertical sectional view on the line 12—12 of Fig. 10; Fig. 13 is a fragmentary top plan view of another modified form of my invention showing a range having two lids or covers which substantially cover the top of the range; Fig. 14 is a fragmentary sectional view similar to Fig. 11; Fig. 15 is a fragmentary vertical sectional view taken substantially on the line 15—15 of Fig. 13; and Fig. 16 is a fragmentary vertical sectional view taken on the line 16—16 of Fig. 13.

Referring now to Figs. 1 to 6 inclusive in which are illustrated the preferred embodiment of my invention, the reference character 1 designates a gas range which includes a flat cooking top 2 beneath which are disposed a pair of cooking and baking compartments 3 and 4 which are separated by a partition 5. The cooking top 2 is provided with a plurality of openings 6, 7, and 8 over which are disposed grids 9, 10, and 11, respectively. Arranged beneath each of the grids are a plurality of cooking top burners. The reference characters 12, 13, 14, 15, 16, and 17 designate the gas supply cocks which serve to control the supply of gas to the cooking top burners. It will appear from Fig. 1 that the cooking top has arranged thereon three groups of cooking top burners and disposed over the burners are covers or lids 18, 19, and 20, respectively. The reference characters 21 and 22 designate the handles for the oven doors which serve to close the compartments 3 and 4. Disposed at the rear of the range and secured thereto in any suitable manner is an extension plate 23 which is preferably formed in one piece and which has a flat portion disposed in substantially the same plane as the cooking top and an upwardly extending portion 24 which forms the back wall of the range. The central portion of the back wall 24 is shaped as

shown at 25 in Fig. 7. Extending substantially entirely across the back of the range is a flue 26 which is substantially rectangular in section. This flue is preferably secured to the extension plate 23 and has communication with the cooking compartments 3 and 4 by means of connections 27 and 28, as shown most clearly in Fig. 2. The flue is provided on its rear side with an enlarged portion 29 in which is provided an opening 30 to which may be connected a flue pipe leading to a chimney. Disposed within the flue and dividing it into two compartments is a baffle 31 which serves to prevent products of combustion from one compartment escaping into the other compartment. The plate 23 at the central portion thereof is cut away as shown at 32 to provide a slot or opening to receive the cover or lid 19. The plate 23 is also provided with cut-out portions 33 and 34 which serve to provide openings which receive the lids 18 and 20. Secured to the back wall of the range and extending vertically thereof are a pair of guides 35 and 36 in which is slidably mounted a slide 37. The cover 19 is secured to the slide 37 by means of a pair of hinges 38 and 39. A stop 40 is provided for limiting the downward movement of the slide 37. The cover 19 when in the open position is shown most clearly in Fig. 4.

Also mounted on the rear wall at the rear of the range and extending transversely thereof are a pair of guides 41 and 42 in which is slidably mounted a guide plate 43 which is connected with the cover plate 18 by means of hinges 44 and 45. When the cover plate 18 is opened, it is moved to the position shown in Fig. 4. The bottom ends of the guides 41 and 42 are supported by means of a pair of plates 46 which are secured to the back of the range, as shown most clearly in Fig. 4. The reference character 47 designates a stop for limiting the downward movement of the guide 43. Disposed at the opposite side of the range and at the rear thereof and extending vertically are a pair of guides 48 and 49 which receive therein a slide 50 which is connected with the cover 20 by means of a pair of hinges 51 and 52.

It will now be seen that the range has a flat cooking top beneath which are disposed a pair of cooking compartments and that there are a plurality of top burners arranged in groups in openings provided in the cooking top, and a flue disposed at the back of the range and connected with the pair of cooking compartments. The top burners are covered by lids or covers which are adapted to be moved to a position to render the same accessible. The two lids which are disposed at the opposite sides of the range when opened are moved to a position rearwardly of the flue while the lid which covers the central group of burners when opened is moved to a position forwardly of the flue.

The reference character 53 designates a flue pipe which leads upwardly through an opening 54 provided in the central back-turned portion of the back plate.

In Figs. 7 to 9 inclusive, there is disclosed a modified form of range which has a flat cooking top 55 beneath which are disposed a pair of ovens or cooking compartments 56 and 57. The cooking top is provided with a pair of openings which extend from front to rear and are disposed adjacent each side of the range. Covering these openings are a pair of grids 58 and 59 beneath which are disposed the cooking top burners. 75 Covering the cooking top burners are a pair of

covers or lids 60 and 61. Secured to the back of the range in any suitable manner is an extension plate 62 which is shaped as shown most clearly in Figs. 7 and 9. Disposed at the rear of the range and extending substantially across the same is a flue 63 which is shaped as shown most clearly in Fig. 8 and which has communication with the ovens 56 and 57 by means of connections 64 and 65. The extension plate 62 is provided on each side thereof with cut-out portions 66 and 67. Secured to the back wall of the range and extending transversely thereof are a pair of guides 68 and 69 which receive therein a guide plate 70 which is secured to the cover 60 by means of hinges 71 and 72. Disposed at the opposite side of the range are a pair of guides 73 and 74 which receive therein a guide plate 75 which is connected with the cover 61 by means of hinges 76 and 77. When the covers 60 and 61 are opened to provide access to the top burners, they slide into the openings 66 and 67. The reference characters 78, 79, 80, and 81 designate the gas control cocks for controlling the supply of fuel to the top burners. The reference characters 82 and 83 designate the handles to the oven doors. This form of the invention is substantially identical with the form of the invention shown in Figs. 1 to 6, inclusive, except that there are only two cover plates which when opened are moved to a position forwardly of the flue. The flue is provided with a baffle plate 84 which serves to prevent the products of combustion escaping from one oven to the other. This flue is adapted to be connected with the chimney by a suitable flue pipe not shown.

In Figs. 10, 11, and 12 there is disclosed another form of my invention showing a range having a flat top and an oven disposed at one side and two groups of cooking top burners disposed at the other side together with a pair of lids one of which covers the cooking top burners and the other of which extends over the top of the oven compartment. This form of the invention embodies a cooking top 85 having a pair of openings 86 and 87 therein in which are positioned grids 88 and 89 below which the cooking top burners are disposed. Both groups of cooking top burners are covered by a single cover plate 90. Disposed at the rear of the range is an extension plate 91 having a horizontal portion which is disposed in the same plane as the top of the range and a vertically extending back portion 92 which forms a back plate. The front face of the extension plate is provided with an opening or cut-out portion 93 and secured to the back of the range and extending vertically thereof are a pair of guides 94 and 95 which slidably receive a guide plate 96 which is connected with the lid or cover plate 90 by means of a pair of hinges 97 and 98. Disposed at the back of the range is a flue 99 which is shaped as shown most clearly in Fig. 11 and is connected with the oven compartment by means of a connection 100 shown in Fig. 12. The flue is provided with a flue outlet or opening 101 adapted to be connected with a flue pipe not shown. The extension plate 91 is provided at the rear thereof with an elongated slot or opening 102. Secured to the back wall of the range are a pair of guides 103 and 104 which slidably receive therein a guide plate 105. Extending over the right hand side of the range is a cover plate or lid 106 which is substantially co-extensive with the oven top and which is connected with the guide plate 105 by means of a pair of hinges 107 and 108. The lid or cover plate 106 is of the same 75

size and shape as the lid 90 and is substantially coextensive with the top of the oven and serves to cover that portion of the range when the range is not in use. The reference characters 109, 110, 5 111, 112 designate the gas control cocks which control the supply of gas to the cooking top burners. The reference character 113 designates the handle to the oven door.

It will now be seen that in this form of range, 10 there is provided a pair of lids one of which covers the cooking top burners and the other of which covers the top of the oven compartment and that when either of these lids is opened, it may be slid downwardly through the slots provided at the rear of the range, one of the covers being disposed behind the flue and the other disposed in front of the flue.

In Figs. 13 to 16 inclusive there is disclosed another form of my invention which embodies a 20 range having a flat cooking top and two ovens disposed therebelow. This range has no cooking top burners but the tops of the ovens are covered by lids 114 and 115 which are rectangular in shape and cover substantially the entire top of the range. The covers or lids 114 and 115 cover substantially the entire top of the range to protect the range when it is not in use so that the top of the range may be used as a table without becoming scarred or marred. Secured to the back of 25 the range in any suitable manner is an extension plate 116 having a vertically extending back portion 117. Also secured to the back of the range is a flue 118 which is connected with both of the ovens and which also is provided with a flue outlet 119.

Disposed within the flue is a baffle plate 120 which serves to prevent the products of combustion from one oven escaping into the other. The extension plate is provided at one side with an 40 elongated cut-out portion 121 and secured to the back wall of the range are a pair of guides 122 and 123 which slidably receive therein a guide plate 124 which is connected with the cover plate 114 by means of a pair of hinges 125 and 126. The extension plate 116 is provided at the opposite side thereof with a cut-out portion or slot 127 and secured to the back of the range and extending vertically thereof are a pair of guides 128 and 129 which slidably receive therein a guide plate 130 which is connected with the cover 115 by means of a pair of hinges 131 and 132. The guides 128 and 129 are secured to the back wall of the range in any suitable manner, such as 50 plates similar to the plates 46 shown in Fig. 4.

It will thus be seen that the range is provided with a pair of cover plates or lids which when opened are received within the slots provided in the extension plate, one of the cover plates being disposed rearwardly of the flue and the other forwardly of the flue.

It will now be clear that I have provided a gas range which will accomplish the objects of the invention as hereinbefore stated. The embodiments of the invention herein illustrated are to be considered as merely illustrative and not in a limiting sense as various changes may be made in the details of construction and arrangement of parts without departing from the spirit of my 65 invention. For example, suitable springs may be provided for facilitating the opening and closing of the lids. If desired, flue outlets may be provided at the rear of the range instead of through the top of the extension plate. Various 70 other changes may be made without departing

from the spirit of my invention and it is to be understood that the invention is limited only in accordance with the scope of the appended claims.

Having thus described my invention, what I claim is:

1. A range having a flat cooking top and one or more cooking compartments disposed therebelow, a plurality of top burners arranged within openings provided in said cooking top, a flue arranged at the back of said range and connected with said cooking compartment or compartments, a plurality of lids adapted to be moved from a position to cover said top burners to a position to render said burners accessible respectively, means disposed rearwardly of said flue for receiving one 15 of said lids when in the open position, and means disposed forwardly of said flue for receiving another of said lids when in the open position.

2. A range having a flat cooking top in which are arranged a plurality of top burners which 20 are disposed in spaced groups, a pair of lids normally covering said groups of burners but movable to a position to render such burners accessible, one or more ovens arranged below said cooking top, a flue disposed at the rear of said range and extending across a substantial portion of the back wall thereof, guiding and receiving means disposed rearwardly of said flue for receiving one of said lids and guiding and receiving 25 means disposed forwardly of said flue for receiving the other lid.

3. A range having a cooking top having three spaced openings therein in each of which is arranged one or more top burners, said burners being disposed along each side of said top and also at the rear portion thereof, an oven disposed below said cooking top, a flue extending across the back of said range and connected with said oven, a lid for each of said burner openings movable to a 40 position rearwardly of said range, means disposed at one side of said flue for receiving one of said lids and means disposed at the opposite side of said flue for receiving the other two lids when such lids are moved to a position to render such 45 burners accessible.

4. A gas range having a flat top and one or more cooking compartments disposed therebelow, a flue arranged at the back of said range and connected with said cooking compartment or compartments, a plurality of lids normally extending over said cooking top but movable to a position rearwardly of the range top, means disposed rearwardly of said flue for guiding and receiving one of said lids when it is opened and means disposed forwardly of said flue for guiding and receiving another of said lids when it is opened.

5. A gas range having a flat top and one or more cooking compartments disposed therebelow, a flue arranged at the rear of said range and connected with said cooking compartment or compartments, a pair of independently movable lids which extend over the top of said range, an extension plate disposed at the rear of said range and constituting a continuation of said top and having a pair of slots therein providing a pair of openings which are disposed parallel with and in substantially the same horizontal plane as said top, one of said slots being disposed forwardly of said flue and the other slot being disposed rearwardly of said flue, and means for guiding said lids respectively into said slots when the lids are opened.

6. A gas range having a flat cooking top having a pair of spaced openings therein in each of 75

which is arranged one or more top burners, a pair of lids normally covering said top burners, an extension plate secured to the rear of said range and having a pair of slots therein forming vertically disposed openings which are disposed in substantially the same horizontal plane as said cooking top, an oven disposed below said cooking

top, a flue for said oven disposed below said plate and between said pair of slots and guiding and receiving means for each of said lids disposed at the rear of said range for guiding said lids into said openings when the lids are opened. 5

JOHN G. HOFF.
